[57] ABSTRACT

[21] Appl. No.: 330,417

A device for counting articles capable of by far speeding up the counting time, which comprises a plurality of gates through which the articles are fed, a plurality of detecting means provided on the respective gates for generating a signal upon detection of the article, a plurality of memory-readout circuits connected to the respective detecting means and adapted to memorize the signals therefrom, a sweep signal generator for periodically reading out the signals memorized by said memory-readout circuit, a logical circuit and a digital counter or an analogic indicator for integrally indicating signals obtained through said logical circuit.

COUNTING DEVICE HAVING MEMORY-READOUT AND LOGIC CIRCUITS

This invention relates to a counting device and more particularly to a counting device capable of by far reducing the time required for counting articles.

In a conventional counting device, such as a coin counting device, coins are fed through one passage where they are detected through an optical or mechanical means and converted into pulse signals for actuating a counter to indicate the number of coins.

With this conventional counting device, however, the counting speed could be hardly improved even by quickening the feeding speed of the coins, since the coins are fed and passed through one passage in such a coin counting device.

This invention is made to overcome the above-mentioned problem and therefore it is an object of the present invention to provide a device for counting articles, in which a conveyor means is provided for transporting the articles and a plurality of passages are provided for detecting a plurality of articles simultaneously, thereby to improve the counting speed very much.

It is another object of the present invention to provide a device for counting articles, in which a conveyor means is adapted to be intermittently driven to even the articles to be detected, without overlapping each other.

It is a further object of the present invention to provide a device for counting articles, in which a conveyor means is adapted to be driven continuously so long as the articles are fed in an even position without overlapping each other.

According to the present invention, there is provided a counting device comprising a hopper; a conveyor driven by a motor and provided below said hopper; a chute disposed adjacently to the forward end of said conveyor, inclined downwardly of said forward end of the conveyor and provided with a plurality of gates; photoelectric detecting means provided on the respective gates and adapted to generate a pulse signal upon detection of articles to be counted; a plurality of memory-readout circuits respectively connected to the corresponding photoelectric detecting means and adapted to memorize the pulse signals from said photoelectric detecting means for a predetermined time; a sweep signal generator adapted to generate a sweep signal for periodically reading out the signals memorized by said memory-readout circuit; a logical circuit for obtaining logical sum of each of the signals read out through said sweep signal generator; and a display means for integratingly indicating the number of the signals from said logical circuit.

The invention will be better understood from the following description taken in connection with the accompanying drawings in which:

FIG. 1 is a perspective view of a counting device in accordance with the present invention;

FIG. 2 is a cross sectional view of FIG. 1;

FIGS. 3 and 4 are side views of a switch means for a motor employed in the present invention, showing its operating condition;

FIG. 5 is a diagram of an electric circuit for controlling the motor;

FIG. 6 is an explanatory-view of photoelectric detecting means employed in this invention;

FIG. 7 is a cross sectional view of FIG. 6 taken along line VII—VII;

FIG. 8 is a block diagram of a counting circuit;

FIG. 9 is an electric diagram of a part of FIG. 8, and

FIG. 10 is a timing chart of signals of the counting circuit shown in FIG. 8.

Referring now to the drawings, there is illustrated a counting device embodying the present invention, which has a frame 1, a hopper 2 fixed to said frame 1 at the upper portion thereof and a conveyor 3 provided under said hopper 2. A lower front plate 2a of said hopper 2 is provided to form a suitable opening for feeding articles 4 to the conveyor 3. The articles 4 charged into said hopper 2 are thus fed onto the conveyor 3 and transported through the opening defined by said lower front plate 2a of the hopper 2, according to the movement of the conveyor 3. Said conveyor 3 is stretched between a drive roller 3a and another roller 3b which are rotatably provided on the frame 1. A belt 3f is put on between a pulley 3d of a motor 3c mounted on the frame 1 and a pulley 3e of said drive roller 3a. A chute 5 is fixed to the frame 1 so as to be adjacent to the forward end of said conveyor 3 and inclined downwardly of said forward end of the conveyor 3. This chute 5 has a plurality of gates 5b formed identically by partitions 5a, according to the size of the articles 4 to be counted. To each of said gates 5b is provided a photoelectric detecting means 6 consisting of a light source 6a and a light receiver 6b such as CdS. The photoelectric detecting means 6 is mounted on the respective gate 5b at a position one sided from the longitudinal central line of said gate 5b. If said photoelectric detecting means 6 is centrally mounted, a signal can hardly be obtained when the articles 4 are continuously fed close to one another. A vibrator 7 is mounted on the chute 5 to give vibration to said chute 5 so that the articles 4 thereon may fall down smoothly.

Numeral 8 designates a detecting plate pivotably fixed to the frame 1 so as to be disposed above the conveyor 3 in height just sufficient to pass one article 4 in the even position. Said detecting plate 8 has a spring 8a fitted thereto to urge said plate 8 toward a microswitch 9 fixed to the frame 1, pressing a movable contact 9a of said micro-switch.

As shown in FIG. 5, numeral 10 designates an oscillator which generates rectangular pulse at given intervals. An output terminal of the oscillator 10 is connected to a normally closed contact of the micro-switch 9. A normally opened contact of said micro-switch 9 is connected to a ground and a movable contact thereof is connected to the base of a PNP type transistor Tr through a resistor R₁. The emitter of said transistor Tr is connected to a positive terminal of a power source and the collector thereof to the gate of a bilateral controlled rectifier such as TRIAC (Trade name of the product manufactured by G.E.) T through a resistor R₂. A first terminal of an A.C. power source E and a second terminal thereof is connected to another terminal of said A.C. power source E through said motor 3c and a power switch S.

In operation, it will be seen that when the article 4 are charged into the hopper 2, they are gradually fed onto the conveyor 3 and transported by said conveyor 3 to the chute 5, if the power switch S is closed in this stage and the TRIAC T is in the on position. At this time, if the detecting plate 8 is not displaced and kept in such a position for keeping the contact 9a of the mi-

cro-switch 9 in the condition as shown in FIG. 5, to wit, the articles 4 are transported in even state without overlapping one another as shown in FIG. 3, the base of the transistor Tr is at a grounding potential to allow a base current to flow and accordingly, a collector current to flow to the gate of the TRIAC T through the resistor R₂. As a result, said TRIAC T is turned on to rotate the motor 3c.

On the other hand, if some of the articles 4 are fed overlapping one another as shown in FIG. 4, they will displace the detecting plate 8 against the action of the spring 8a and the contact 9a of the micro-switch 9 is switched from the position of FIG. 5 so that the base of the transistor Tr is connected to a rectangular pulse generator 10 through the resistor R₁. In the transistor Tr, a base current flows at 0 level of the rectangular wave and, then, a collector current flows to the gate of the TRIAC T through the resistor R₂ to turn on said TRIAC T. The motor 3c is then rotated. At a high level of said rectangular wave, a base current does not flow and the transistor Tr is turned off so that a gate current does not flow in the TRIAC T and said TRIAC is turned off. Accordingly, the motor 3c is not rotated. It is thus seen that when the base of the transistor Tr is connected to the oscillator 10, the motor 3c is adapted to be driven and halted repeatedly according to the level of the rectangular wave. Thus, the conveyor 3 is driven intermittently, giving shocks to the articles 4 to make them even and feed to the chute 5.

The articles 4 fed to the chute 5 slide down smoothly since said chute 5 is inclined downwardly and vibrated by the vibrator 7, and are passed through respective gates 5b formed by the partitions 5a. When these articles 4 pass through the gates 5b, they interrupt lights from respective light sources 6a, thereby to be detected by the respective light receivers 6b to generate signals. These signals will be counted through a counting circuit as mentioned later to indicate the number of the articles 4. In this embodiment of the present invention, since a plurality of gates 5b are provided, the sum of the articles 4 passed through the respective gates is indicated as the number of the articles 4.

The counting circuit is explained referring to FIG. 8 wherein I₁, I₂, I₃ — I_n are input terminals thereof connected to the respective light receivers 6b and adapted to receive input pulse signals therefrom.

A₁, A₂, A₃ — A_n are memory-readout circuits to which said input terminals I₁, I₂, I₃ — I_n are connected, respectively. Each of said memory-readout circuits A₁, A₂, A₃ — A_n includes a memory circuit 11, a delay circuit 12, a monostable multivibrator 13, a gate circuit 14 and a build-up delay circuit 15. The signals received by said input terminals I₁, I₂, I₃ — I_n are memorized for a predetermined period of time, read out by signals from a sweep signal generator B as mentioned below and applied to a logical circuit, more particularly a NOR circuit C.

The sweep signal generator B has output terminals corresponding to the respective input terminals I₁, I₂, I₃ — I_n of the memory-readout circuits A₁, A₂, A₃ — A_n and connected to said memory-readout circuits A₁, A₂, A₃ — A_n to transmit sweep signals thereto sequentially. As the sweep signal generator B, a ring counter or a shift register may be employed to generate sweep signals respectively for the input terminals I₁, I₂, I₃ — I_n with a cycle of T. The high level of such sweep signals is determined to last for t₄ period of time. Through the

NOR circuit C, logical sum of each of the signals memorized by the memory-readout circuits A₁, A₂, A₃ — A_n and read out through the sweep signal generator B is obtained. In other words, the NOR circuit C is adapted to produce an output or a signal upon receipt of an output or a signal from the memory-readout circuit A₁, A₂, A₃ — A_n through the sweep signal generator B. A display means D may be a digital counter which is adapted to count one upon every receipt of the output or signal from said NOR circuit.

FIG. 9 shows the memory-readout circuit A₁ more particularly. The memory circuit 11 forms a flip-flop circuit of NAND gates 11a and 11b having two input terminals. An input terminal of the NAND gate 11a is connected to the input terminal I₁ and an input terminal of the NAND gate 11b is connected to the delay circuit 12. The delay circuit 12 is composed of a resistor R₁ and a condenser C₁ and adapted to apply an output to said NAND gate 11b after a time delay determined by said resistor R₁ and said condenser C₁. An input terminal of said delay circuit 12 is connected to an output terminal of the monostable multivibrator 13. This monostable multivibrator 13 is composed of a NAND gate 13a, a condenser C₂, a resistor R₂ and an inverter 13b. The gate circuit 14 has a NAND gate one input terminal of which is connected to an output terminal of the NAND gate 11a of said memory circuit 11 and the other input terminal of which is connected to an output terminal of the build-up delay circuit 15. An output terminal of said gate circuit 14 is connected to an input terminal of the monostable multivibrator 13 and an input terminal of the NOR circuit C. The build-up delay circuit 15 includes resistors R₃ and R₄, a condenser C₃, inverters 15a and 15b and a diode D₁. An input terminal of said circuit 15 is connected to one output terminal of the sweep signal generator B and the output terminal thereof is connected to one input terminal of the gate circuit 14. The build-up delay is obtained by the resistor R₃ and the condenser C₃ and falling is effected by the diode D₁ without any delay.

The other memory-readout circuits A₂, A₃ — A_n are composed identically with the above specified memory-readout circuit A₁.

It will be thus seen in operation that when a low level signal 11a₁ is applied to the input terminal I₁ of the memory circuit 11, the output 11a₁' obtained therefrom is a high level signal and that when a reset signal (low level) is applied to the input terminal of the NAND gate 11b of the memory circuit 11, the output of said memory circuit 11 becomes low level. Accordingly, when a sweep signal b₁ is transmitted by the sweep signal generator B under the condition an input signal has been applied to the input terminal I₁, this sweep signal is applied as a signal 15₁ to the input terminal of the gate circuit 14 through the build-up delay circuit 15 after delay of t₁ determined by the resistor R₃ and the condenser C₃. Since this gate circuit 14 has already received a high level signal from the memory circuit 11, the output signal therefrom is of low level. When the output signal 14₁ from the gate circuit 14 is applied to the NOR circuit C, a high level signal O₁ is generated to actuate the digital counter D and count one.

On the other hand, since the output signal 14₁ from the gate circuit 14 is applied to the monostable multivibrator 13, an output signal 13₁ from said monostable multivibrator 13 has width of t₂ and a signal 11b₁ is ap-

plied to the input signal of the NAND gate 11b which is a resetting input terminal of the memory circuit 11 after delay of t_3 obtained by a time constant circuit composed of the resistor R_1 and the condenser C_1 of the delay circuit 12. The memory circuit 11 is thus reset and restored to its original position to cancel the memory. The output signal 14₁ from the gate circuit 14 normally has width of t_3 .

A second stage circuit A₂ is operated identically with the above-mentioned first stage circuit A₁. When an input signal 11a₂ is applied to the input terminal I₂, an output signal 11a₂' is generated and an output signal 14₂ is obtained from the memory-readout circuit A₂. Subsequently, an output signal O₂ is produced from the NOR circuit to actuate the digital counter D, counting one, and indicate two.

However, as shown in FIG. 10, if an input signal 11a₃ is applied to an input terminal I₃ just before fall of the sweep signal b₃, an output signal O₃ has a width reduced than the above-mentioned cases. At this time, even if the input signal 11a₃ remains after the sweep signal has disappeared, the memory circuit 11 can be surely reset insofar as t_2 is determined to be longer than the input signal 11a₃, since the resetting signal is retained for period of t_2 by the monostable multivibrator 13.

Accordingly, there must be a relation $t_5 < t_2$ wherein t_2 is a width of an input signal applied to the input terminal of the memory circuit 11 and t_2 is a width of an output signal of the monostable multivibrator 13. There must be another relation $t_4 = T/n$ wherein t_4 is a width of an output signal of the sweep signal generator B and T is a cycle of the sweep signals. T should be determined to be shorter than any cycle of the input signals 1a₁, 1a₂ — 1a_n applied to this counting circuit.

The similar operation will be effected in the following memory-readout circuits (A₄ — A_n).

In the present circuit arrangement, when a signal is not applied to an input terminal of the memory-readout circuit, an output is not produced from the gate circuit 14 if the sweep signal is applied to the build-up delay circuit 5.

Thus, signals arbitrarily applied to the input terminals I₁, I₂, I₃ — I_n of the memory-readout circuits A₁, A₂, A₃ — A_n irregularly, are drawn out at the output of the NOR circuit C at intervals of t_4 . The digital counter D, then, counts one at every arrival of the signal from said NOR circuit to indicate the number of the input signals.

By combining input terminals I₁, I₂, I₃ — I_n to the coin detecting means 6, it becomes possible to count coins passed randomly through n gates.

In the foregoing, a digital counter D is employed for indicating the number of the coins, but analogic indication means such as a meter may be alternatively employed for indicating the number of the articles applied in unit time.

According to the present invention, when a plurality of articles are fed simultaneously or at arbitrary inter-

vals, the number of the articles can be accurately counted.

What is claimed is:

1. A counting device comprising a hopper; a conveyor driven by a motor and provided below said hopper; a chute disposed adjacently to the forward end of said conveyor, inclined downwardly of said forward end of the conveyor and provided with a plurality of gates; photoelectric detecting means provided on the respective gates and adapted to generate a pulse signal upon detection of articles to be counted; a plurality of memory-readout circuits respectively connected to the corresponding photoelectric detecting means and adapted to memorize the pulse signals from said photoelectric detecting means for a predetermined time; a sweep signal generator adapted to generate a sweep signal for periodically reading out the signals memorized by said memory-readout circuit; a logical circuit for obtaining logical sum of each of the signals read out through said sweep signal generator; and a display means for integrally indicating the number of the signals from said logical circuit.
- 10 2. A counting device as claimed in claim 1, wherein each of said memory-readout circuits includes a memory circuit adapted to be turned on to produce an output upon receipt of the input signal from said photoelectric detecting means and kept turned on until a signal is applied thereto from a delay circuit connected in said memory-readout circuit; and a gate circuit adapted to produce an output when the output signal from said memory circuit and the sweep signal from said sweep signal generator are applied thereto; said delay circuit being adapted to apply the output signal from said gate signal to said memory circuit after the predetermined time delay to turn off said memory circuit.
- 15 3. A counting device as claimed in claim 2, wherein said memory-readout circuit further includes a build-up delay circuit which is adapted to apply said sweep signal from the sweep signal generator to said gate circuit after a predetermined time delay.

- 20 4. A counting device as claimed in claim 2, wherein said memory-readout circuit further includes a monostable multivibrator for making the width of said output signal from said gate signal larger than that of the input signal from the photoelectric detecting means.
- 25 5. A counting device as claimed in claim 1, which further comprises a detecting means disposed over said conveyor in height just for passing one article thereunder and adapted to be displaced by the articles fed on said conveyor overlapping one another; a switch adapted to be operated by the displacement of said detecting means; and a motor control circuit having a pulse oscillator electrically connected when said switch is operated by the displacement of the detecting means to intermittently drive said motor.
